UNITED STATES PATENT OFFICE.

NATHAN C. BUTLER, OF CLEVELAND, OHIO.

FUSE PLUG.

Application filed October 8, 1920. Serial No. 415,628.

To all whom it may concern:

Be it known that I, NATHAN C. BUTLER, a citizen of the United States, residing at Cleveland, in the county of Cuyahoga and State of Ohio, have invented certain new and useful Improvements in Fuse Plugs, of which the following is a specification.

This invention relates to fuse plugs for use in electric installations.

10 The object of the invention is to provide a fuse plug which includes a main member having an exterior threaded contact for engagement in a suitable socket, and a removable member carrying the fuse which has 15 its ends secured to a center contact and to a peripheral contact respectively, the last named contact being removably connected to the main contact member.

It is also the purpose of this invention 20 to provide a removable fuse carrying member with an insulator extension between the two contacts for preventing arcing, to connect the fuse element to the peripheral contact in a manner to prevent rotation thereof, and to further arrange the removable member in a manner such as it will hold the mica or other transparent element in place in the main member. Other features of the invention are the provision of suitable gas 25 vents, and the provision of suitable recesses or grooves for holding the fuse wire in place.

Other features of the invention will more fully and at large appear from the following description, drawings and claims.

35 Referring to the drawings, Fig. 1 is a side elevation of a plug with parts broken away; Fig. 2 is a sectional view of the main portion; Fig. 3 is a bottom plan view of the main member; Fig. 4 is a sectional view of the removable fuse member; Fig. 5 is a bottom plan view; Fig. 6 is a top plan view with the fuse wire removed; Fig. 7 is a modified form partly in section of the removable fuse member; Fig. 8 is a modified form of 40 the main member with the threaded conductor shell broken away; Fig. 9 is a sectional view of the main member of Fig. 8 with the conductor shell removed.

50 In the arrangements shown in Figs. 1 to 6, the main fuse member 1 is provided with a

central window or opening 2 communicating with an enlarged fuse chamber 3. The chamber 3 is larger in diameter than opening 2 to provide a shoulder 4 which is interrupted to form corrugations 5. These corrugations merge into corrugations 6 formed on the main wall of the chamber 3. The corrugations 5 and 6 provide means for centering and holding a glass or mica disc 7 which provides a window in the main fuse member. These corrugations also afford a passage between the chamber 3 and the outside atmosphere for the escape of gases.

The main fuse member is provided with a threaded portion 8 adapted to receive a threaded conductor shell 9 which is secured in place by depressing a portion 10 of the shell 9 into a longitudinally disposed groove or channel 11, arranged in the exterior of the threaded portion 8. This channel 11 communicates with a radially disposed recess 12 providing communication between the channel 11 and the chamber 3 whereby gases are permitted to escape. The threaded shell 9 extends beyond the main fuse member as shown in Fig. 2 for a purpose which will later appear.

The removable fuse member comprises a body portion 13 having a central opening therein for receiving a center contact 14 which is preferably in the form of a bifurcated rivet, the prongs of the rivet being spread in a central opening 15 formed in the body portion. The opening 15 is an enlargement of the opening which receives the shank of the contact 14. The annular extension 16 is formed of insulating material integral with the main body portion 13. This member is slightly tapered on its exterior and has an annular enlargement 17 at its base where it joins the main body portion. This enlargement 17 is provided with diametrically opposed longitudinally extending grooves 18 for a purpose to be later described. The main body portion 13 is slightly reduced and threaded to receive the threaded portion 19 of the fuse contact 20. This contact has an upwardly extending sleeve 21 which is forced down on the enlargement 17. The extension 16 is pro-

vided at its upper end with notches 22 which are adapted to receive the fuse wire or strip 23 which is soldered to the center contact 14. The fuse wire is passed through the notch 22 as stated and into one of the grooves 18 and there soldered or electrically connected to the sleeve 21. The solder and fuse wire form a means for preventing rotation of the contact 20. The threaded portion 19 of the contact 20 is adapted to screw into the threaded extension of the shell 9 of the main fuse member.

It will be seen from the foregoing that the removable fuse carrying member comprises the insulator body portion and extension, the center contact 14 and the peripheral contact 20, together with a fuse which is electrically connected to these parts, and that this member may be assembled and removably secured in the main fuse member; and when secured the upper end of the extension 16 will hold the glass or mica disk 7 in place against the corrugations 5. Suitable gas vents are provided by the corrugations 25 and by the channel 11 and recess 12. It is to be understood that the depression of the portion 10 of the shell 9 does not entirely close the recess 11 and that the threaded member 10 does not close the upper end of recess 11 when in fully engaged position, as seen in Fig. 2.

In the modification of the removable fuse member shown in Fig. 7, the extension 16' is not only provided with the notches 22 but with longitudinally disposed grooves 24 extending therefrom to the main body portion 13'. Here the contact 20 engages the fuse member by friction alone.

In the modification shown in Figs. 8 and 9 the main fuse member is formed as a transparent glass body 25 having the integral extension 26 forming the inner fuse chamber 27. Otherwise the structure in this modified form is the same as in the main form of device above described, including the groove 11 and recess 12 for permitting escape of gases, as well as the depressed portion 10 for securing the socket engaging member 9 in fully engaged position upon the main insulator member 1.

What I claim is:

1. A fuse plug comprising a socket engaging member formed with an interior chamber having openings through the ends of said member, a closure for one end of said member and positioned within the same, and means normally providing a gas vent from said chamber past said closure, a fuse member removably secured in the other end of said chamber and provided with electric connections through said members.

2. A fuse plug comprising a socket engaging member formed with an interior chamber having openings through the ends of said member, one of said ends having an

interior interrupted seat, a closure engaging said seat so as to permit escape of gases past the same, a fuse member removably secured in the other end of said chamber and electric connections through said members.

3. A fuse plug comprising a main insulator or member formed with an interior chamber having openings through the ends of said member, one of said openings having an interrupted seat, a closure engaging said seat and permitting escape of gases past the same, a socket engaging member upon said insulator or member, a fuse member removably secured in the other end of said insulator member and provided with electric connections through said socket engaging member, and means permitting escape of gases from said chamber out between said insulator and socket engaging members.

4. A fuse plug comprising a socket engaging member formed with an interior chamber having openings through the ends of said member and having a seat at one opening, a closure for said one opening, a fuse member removably secured within the other end of said chamber and holding said closure against said seat, said fuse member having electric connections through said socket engaging member.

5. A fuse plug comprising a socket engaging member, a fuse member removably secured by positive locking engagement in said first named member, said fuse member comprising a hollow elongated insulator portion, a fuse having one end secured within said insulator portion and its other end secured outside thereof, and electric connections through said fuse and said socket engaging member.

6. A fuse plug comprising a socket engaging member, a fuse member removably secured in said first named member, said fuse member comprising a hollow elongated insulator portion, a contact extending through said insulator portion, a conducting element secured entirely on the outside of said insulator portion and adapted for conductive engagement with said socket engaging member, and a fuse having its ends attached to said contact and conducting element, respectively.

7. A fuse plug comprising a socket engaging member formed with an interior chamber having openings through the ends of said member, a closure for one of said openings, a fuse member removably secured within said other opening and holding said closure in position, said fuse member comprising a hollow insulator portion having a depression in the end thereof which engages said closure, a fuse having its ends attached to the inside and outside of said insulator portion, respectively, and lying in said depression, and electric connections through said fuse and said socket engaging member.

- 8: A fuse plug comprising a main insulator member, a socket engaging member carried thereby, a fuse member comprising an insulator member, a contact member carried entirely upon the outside of said last named insulator member and having electric connection with said socket engaging member, a second contact member carried by said last
- named insulator member, a fuse having its ends attached to said contact members, respectively, and an insulator wall between said contacts. 10

In testimony whereof I hereby affix my signature.

NATHAN C. BUTLER.
